UNITED STATES PATENT OFFICE.

VIRGINIA ROSALIE COXE, OF KNOXVILLE, TENNESSEE.

PLAYING-CARD.

SPECIFICATION forming part of Letters Patent No. 718,917, dated January 20, 1903.

Application filed February 17, 1902. Serial No. 94,492. (No model.)

To all whom it may concern:

Be it known that I, VIRGINIA ROSALIE COXE, a citizen of the United States, residing at Knoxville, in the county of Knox and State 5 of Tennessee, have invented certain new and useful Improvements in Playing-Cards; and I do hereby declare the following to be a full, clear, and exact description of the invention, such as will enable others skilled in the art 10 to which it appertains to make and use the same, reference being had to the accompanying drawings, which form a part of this specification.

My invention relates to playing-cards, and 15 particularly to cards for games to be played by four or six players.

The object of the invention is to produce a game in which the leading cards bear representations or designations of race-horses. I 20 have applied to said game the name "handicap-whist."

Figures 1 to 6, inclusive, illustrate cards each of which is the leading card of a suit. Figs. 7, 8, 9, and 10 illustrate a series of cards 25 which appear in each suit.

The entire pack of cards is composed of six suits, each containing fourteen cards. Each of the race-horse cards illustrated by Figs. 1 to 6, inclusive, represents a race-horse, des-

30 ignated, preferably, by picture, name, and color, the name and color being distinct for each horse. Each of said race-horse cards is the leading card of its suit, the remainder of its suit being made up of the thirteen cards illustrated by Figs. 7, 8, 9, and 10, said thirteen cards taking the color of the leading card. Aside from the leading card, the cards 35 of every suit have the same number and relative value as the cards in a suit in the ordinary pack used for playing euchre, whist, &c. The ace (shown in Fig. 10) is the second of the suit. The cards illustrated by Figs. 7 and 8 are respectively the king and queen of such ordinary playing-cards. These

40 45 50 constitute the third and fourth cards of the suit. The fifth card of the suit (illustrated by Fig. 9) represents a jockey, preferably by picture and name. On each of the leading or racer cards a flag or other suitable device is placed upon one or more corners of the card

and colored to conform to the color of its suit. The third, fourth, and fifth cards are also preferably provided at each corner with a suitable device or emblem bearing the color of the suit to which the card belongs. In the 55 case of the king and queen such emblem or device may be a crown or coronet, and in the case of the jockey such device or emblem may be a jockey's cap.

The ten cards illustrated by Fig. 10 are the 60 ten spot-cards of the pack in ordinary use; but in each of the six suits of my game the spots differ in color from the color applied to the other groups, and the color of the spot-cards in each suit is the same as the color of 65 the racer, king, queen, and jockey cards of the same suit.

One of the six leading or racer cards is made an "advantage" card, said card representing a horse having carried off all prizes and highest stakes. It takes everything, and the suit of that card permanently represents trumps, and every card of that suit counts one to the holder at the end of the hand. Said suit may therefore be called the "advantage" suit. In 70 75 the drawings the card illustrated by Fig. 1 is said advantage card. Its color is blue, indicating the success of its horse "Criterion" in carrying off all prizes and stakes.

The four leading cards illustrated by Figs. 80 2, 3, 4, and 5 designate horses "Tornado," "Drifton," "Longshot," and "Fleetfoot," which are represented in the game as running even and no advantage or disadvantage attaches to them in the game and all have the 85 same relative value. Their colors are respectively red, yellow, purple, and green.

The card illustrated by Fig. 6 designates "Old Bones," a horse that is slow and losing in the races and bearing orange color. This 90 is a "disadvantage" card, having lower value than the other leading cards. Said card handicaps the holder and sets him back one point, and every card of this suit discounts one to the holder, just as every card of the 95 suit to which the advantage card belongs counts one for the holder at the end of the hand. Said suit to which the disadvantage card belongs may therefore be called the "disadvantage" suit.

It will be understood that any desired colors may be chosen as substitutes for those herein mentioned.

The racers or leading cards take everything 5 and have the same value as "jokers."

My improved pack of cards may be used for ordinary card games, after taking out two suits and the six racers.

I claim as my invention—

10 1. A pack of playing-cards, said pack being composed in part of a plurality of cards representing race-horses running even and an advantage card representing a horse winning all races and of a disadvantage card 15 representing a slow or losing horse.

2. A pack of playing-cards, said pack being composed in part of a plurality of cards representing race-horses, running even, and of an advantage card representing a horse winning all races, and of a disadvantage card 20 representing a slow or losing horse, and of cards representing jockeys.

In testimony whereof I affix my signature, in presence of two witnesses, this 14th day of February, in the year 1902.

VIRGINIA ROSALIE COXE.
